Specification for Design.

Patented Jan. 3, 1922.

Application filed March 9, 1921. Serial No. 450,978. Term of patent 14 years.

To all whom it may concern:

Be it known that I, JAMES M. DODDRIDGE, a citizen of the United States, residing in the town of Milton, in the county of Wayne and State of Indiana, have invented a new, original, and ornamental Design for Grave Linings, of which the following is a specification, reference being had to the accompanying drawing, forming a part thereof.

The figure of the drawing is a front elevation of a grave lining, showing my new design.

What I claim and desire to be secured by Letters Patent of the United States, is:

The ornamental design for a grave lining, as shown.

In testimony whereof I have hereunto subscribed my name to this specification in the presence of two subscribing witnesses, this the 7th day of March, 1921, in the city of Richmond, Wayne County, State of Indiana.

JAMES M. DODDRIDGE.
